(57) **CLAIM**

The ornamental design for jewelry, as shown and described.

DESCRIPTION

FIG. 1 is an elevational view of my jewelry.

FIG. 2 is a front elevational view of my jewelry.

FIG. 3 is a rear elevational view of my jewelry.

FIG. 4 is a left side elevational view of my jewelry. The right side is a mirror image of the left side.

FIG. 5 is a top plan view of my jewelry; and,

FIG. 6 is a bottom plan view of my jewelry.

The phantom lines in the figure are for illustrative purposes only and form no part of the claimed design.
